UNITED STATES PATENT OFFICE.

JOHN A. OLSON, OF ROCKFORD, ILLINOIS.

GLASS-POLISHING MACHINE.

1,086,076.

Specification of Letters Patent. Patented Feb. 3, 1914.

Application filed September 12, 1913. Serial No. 789,462.

To all whom it may concern:

Be it known that I, JOHN A. OLSON, a citizen of the United States, residing at Rockford, in the county of Winnebago and 5 the State of Illinois, have invented certain new and useful Improvements in Glass-Polishing Machines, of which the following is a specification.

This invention relates to polishing machines adapted for use in polishing glass surfaces and especially that of polishing bevel surfaces on plate glass.

The object of this invention is to construct a machine for polishing the beveled edges on plates of glass, and one which shall embody also, face polishing means whereby both the beveled and flat faces of a plate of glass may be polished in the same operation.

The further object of this invention is to 20 provide a polishing machine capable of a wide range of adjustment so that the polishing means may be adapted to variously sized plates of glass to polish the bevels of same.

In the accompanying drawings: Figure 1 25 is a side elevational view of my improved glass polishing machine with certain parts in section, the polishing means at the left being shown in an operative position. Fig. 2 is a view looking at the left hand end of 30 Fig. 1. Fig. 3 is a plan sectional view as taken on the line of section 3-3 of Fig. 2.

The frame structure for carrying the polishing means is suspended from overhead beams 4 attached to a ceiling, and comprises 35 two sets of vertical side-bars 5-5 and 6-6 fastened fixedly to said beams, the lower end of the side-bars terminating above a work holding carriage 7 which is mounted upon rollers 8 slideable upon tracks carried by a 40 base 9, and said side-bars being connected at their upper and lower ends by horizontal side rods 10 secured to the outer sides of the side-bars by brackets 11.

Stationary glass polishing means are carried 45 through the side-bars 5, and bodily movable polishing means are carried by a frame mounted slideable upon the horizontal rods 10, this frame comprising side-bars 12 having journal brackets 13 attached to sides 50 thereof and which are mounted slideable upon said rods 10, the side-bars 12 being connected by cross-bars, as likewise are side-bars 5, these cross-bars 14, 15 and 16 forming the direct support to which glass polishing 55 ing devices are attached. The movable polishing frame is adjustable toward and

away from the stationary frame by means of a screw-rod 17 in screw threaded engagement with a bracket 18 carried by the said movable frame and in a collar engagement 60 with the stationary frame, the rod 17 being rotated by a hand-wheel 19.

Since the glass polishing means carried by both the stationary and movable frames are of a like construction I will describe the 65 construction and operation of those means carried by the stationary frame, which description will apply equally well to the movable polishing means.

Journalized in bearings in cross-bars 15 and 16 is a vertical drive-shaft 20 adapted to be 70 suitably driven, having provided a drive pulley 21, and a secondary vertical shaft 22 similarly journalized on said cross-bars, shaft 22 being driven through gear connection 23 75 with the drive-shaft 20. A cross-head 24 has a sleeved end mounted upon each shaft 20 and 22, the lower ends of the sleeves resting upon cross-bar 15 and their upper ends abutting adjustable collars 25 on said shafts, 80 said cross-head being movable vertically to raise and lower simultaneously the said shafts, by a pivoted hand-lever 26 having a link connection with said cross-head. The lower ends of shafts 20 and 22 extend below the cross-bars 16, and journalized upon the end of shaft 20 is a polisher head 27 having a central opening in which is located a bevel gear 28 fixedly mounted upon shaft 20, this gear serving to hold the head 27 from longitudinal displacement on shaft 20, and said head being guided from lateral displacement by two guide rods 29 in screw 85 threaded connection therewith, these rods being guided in slideways 30 and have adjustment nuts 31 at their upper ends, which nuts abut the tops of slideways 30 and limit downward movement of the polisher head 27. A cross-shaft 32 is journalized in polisher head 27, is driven through bevel gear 100 33 in mesh with bevel gear 28, and has attached to its opposite ends through universal joints 34, polishing-wheel arbors 35, mounted fixedly upon each of these arbors is a 105 polishing wheel 36, the periphery of which are tapered to conform with the bevel of a glass plate and are formed with a polishing surface of felt or suitable material. Yoked brackets 37 attached to opposite sides of the polisher head each have a vertically elongated guide face 38 disposed about the inner ends of an arbor 35 whereby said arbor will

be guided free to move vertically but restricted from horizontal swinging movement. Attached to the lower end of shaft 22 is a face polisher 39 of a construction well known in the art. A reservoir 40 for containing water is carried by the frame 5—5 and is provided with stop-cocks 41 on sides adjacent the polishing wheels, which cocks are adapted to discharge water drop by drop into trough-ways leading to said polishing wheels, each trough-way comprising upper and lower trough sections 42 and 43 respectively, section 42 pivoted at its upper end to the reservoir, the sections being link connected at their adjacent ends to allow a desirable vertical movement and the lower section having a brush end 44 resting upon the polishing face of wheel 36.

A plate of glass 45 is placed upon the carriage 9 in a position as shown in the drawings, and the glass polishing means is in a lowered operative position, that is, with its polishing wheels resting upon the beveled surfaces sought to be polished. Assuming shaft 20 to be driven, the cross-shaft 32 will be driven through its bevel gear connection, and thus the polishing wheels 36 rotated. The carriage 9 is then reciprocated by suitable means, thus moving glass plate 45 back and forth under the polishing wheels, this movement together with that of the polishing wheels constituting the polishing operation, and since the polishing wheels are suspended from universal joints, they will rest upon the beveled edges of the glass through their own weight and free to move vertically. To obtain a more pronounced bevel angle by the polishing wheels the polisher head 27 would be raised by its adjusting nuts 31, thus causing the polishing wheels to assume a greater angled position, and when the said head 27 is raised entirely from the operative position by lever 26 said wheels 36 will fall to a lower position as shown at the right in Fig. 1. To polish bevels that are spaced wider apart the polishing wheels may be moved apart upon their arbors the desired distance, and secured in this position. To obtain a still greater distance between two outer polishing wheels the adjacent or inner wheels of both sets of polishing means would be removed, and the frame 12—12 would be adjusted through hand-wheel 19 to obtain the required distance between the two outer polishing wheels. When polishing both bevels with the same device it is desirous to polish also the flat face of glass intermediate said bevels, and such operation is warranted by the provision of the face polisher 39 located at one side and intermediate the two bevel polishing wheels, such location allowing the polisher 39 to over-reach the bevel edges of the glass and thus polish the entire flat surface of the glass. Certain polishing ingre-

dients are applied to the glass face, to be absorbed and worked upon the glass by the felt faced polishing wheels; and it is desirous to keep this polishing material moist, therefore the provision of the trough means 70 for supplying water to the bevel wheels, which means conform to the various movable positions of said wheels, because of their linked construction.

If it should be desirous to polish only the 75 bevel faces of the glass in one operation, the polishing wheel 39 would be removed and the shaft 22 raised, disengaging its gear connection 23, and collar 25 adjusted to hold said shaft in its raised position.

It is evident that the arbors 35 might be lengthened and thus be capable of polishing the bevels of glass of more varied width without resorting to the combination of the two polishing devices as was above described. 85

I claim as my invention:

1. In a polishing machine of the character set forth, a horizontally disposed shaft, an arbor connected to each end thereof by a flexible joint, a polishing wheel mounted 90 upon each arbor, the polishing wheel adapted to rest upon work to be polished, solely supported through said flexible joint and being movable through said joint to various angles relative to said work, and means for 95 rotating said shaft.

2. In a polishing machine of the character set forth, polishing means comprising, two oppositely extending horizontally disposed shafts, each shaft supported at its inner end 100 through a universal joint, a polishing member mounted upon the suspended portion of each shaft, the polishing wheels being vertically movable from said universal joints and adapted to rest upon work being polished and to conform to its angle through said movement, and means for rotating said shafts.

3. In a polishing machine of the character set forth, polishing means comprising, two 110 oppositely extending horizontally disposed arbors, each arbor supported at its inner end through a universal joint, a polishing wheel mounted upon each arbor, means for driving the arbors, and means for allowing 115 the arbors a vertical swinging movement from said universal joints and to retain them from horizontal swinging movement.

4. In a machine for polishing beveled edges of glass, two arbors positioned in 120 substantially parallel vertical planes, a polishing wheel mounted upon each arbor, means for supporting the arbors to allow them a vertical movement and in which they may assume an angled position from the vertical to conform the periphery of their polishing faces to the bevels of the glass, and means for rotating the polishing wheels. 125

5. In a machine of the character set forth, two grinding wheels mounted spaced apart 130

on horizontally disposed axes and adapted to grind bevels, and a face grinding wheel mounted on a vertical axis located intermediate the grinding wheels.

5. 6. In a polishing machine of the character set forth, the combination of a supporting frame, a vertically disposed drive-shaft carried thereby and slidably vertically thereon, a head journaled on the lower portion of 10 said shaft, a horizontally disposed shaft journaled on said head, a gear drive between said drive-shaft and horizontally disposed shaft, a polishing wheel connected to each end of said horizontally disposed shaft 15 through means of a flexible connection, means for holding said head from lateral displacement, and means for moving said drive-shaft vertically.

7. In a polishing machine of the character 20 set forth, the combination of a supporting frame, a vertically disposed drive-shaft carried thereby and slidably vertically thereon, a head journaled on the lower portion of said shaft, a horizontally disposed shaft 25 journaled on said head, a gear drive between said drive-shaft and horizontally disposed shaft, a polishing wheel connected to each end of said horizontally disposed shaft through means of a flexible connection, a 30 slidable connection between the head and supporting frame to hold the head from lateral displacement but allow it vertical movement, adjustable means associated with said connection for limiting the vertical 35 movement of said head, and means for moving said drive-shaft vertically.

8. In a polishing machine of the character 40 set forth, the combination of a supporting frame, a head supported thereby and movable vertically relative thereto, a horizontally disposed shaft journaled on said head, a polishing wheel connected to each end por-

tion of said shaft through a flexible connection adjustable means for limiting vertical movement of said head, means for moving 45 the head vertically, and means for driving said horizontally disposed shaft.

9. In a polishing machine of the character set forth, the combination with an arbor supported at one end through a flexible connection and a polishing wheel mounted on 50 said arbor, of a reservoir, and a communicating liquid guide between the reservoir and polishing wheel periphery, movable to conform to bodily displacement of said polishing wheel.

10. In a polishing machine of the character set forth, the combination with a stationary frame and a frame movable toward and away from same, of polishing means 60 carried by each frame, each comprising a driving member, a horizontally disposed member connected therewith through a flexible connection, a bevel polishing wheel mounted upon the horizontally disposed 65 member, said wheel supporting members being disposed in substantially parallel vertical planes, and means for moving said movable frame relative to the stationary frame.

11. In a machine of the character set 70 forth, two grinding wheels mounted spaced apart on horizontally disposed axes, a face grinding wheel mounted on a vertical axis located intermediate the grinding wheels, said grinding wheel and wheels being movable vertically relative to and independent 75 of each other.

In testimony whereof I have hereunto set my hand in presence of two subscribing witnesses.

JOHN A. OLSON.
